UNITED STATES PATENT OFFICE.

SAMUEL M. RIKER, OF CHESTER, NEW JERSEY.

DESIGN FOR HEEL DECORATION FOR WOMEN'S SLIPPERS.

Application filed June 4, 1929. Serial No. 31,532. Term of patent 3½ years.

To all whom it may concern:

Be it known that I, SAMUEL M. RIKER, a citizen of the United States, residing at Chester, in the county of Morris and State of New Jersey, have invented a new, original, and ornamental Design for Heel Decoration for Women's Slippers, of which the following is a specification, reference being had to the accompanying drawings, forming part thereof.

In said drawings, Figure 1 is a front face view, and Figure 2 is a side edge view of a heel decoration for women's slippers, showing my new design.

I claim:

The ornamental design for heel decoration for women's slippers as shown.

Dated this 29th day of May, 1929.

SAMUEL M. RIKER.
